Primary Examiner — Susan E Krakower*Assistant Examiner* — Jerry Shiuan-Hua Hsu(74) *Attorney, Agent, or Firm* — NIXON & VANDERHYE(57) **CLAIM**

The ornamental design for the hydrofoil vehicle as shown and described.

DESCRIPTION

FIG. 1 is a top, front, right side perspective view of a hydrofoil vehicle according to our new ornamental design; FIG. 2 is a front view thereof; FIG. 3 is a rear view thereof; FIG. 4 is a top view thereof; FIG. 5 is a bottom view thereof; FIG. 6 is a left side view thereof; FIG. 7 is a right side view thereof; and, FIG. 8 is a top, rear, right side perspective view thereof. The broken lines illustrate portions of the hydrofoil vehicle which form no part of the claimed design.
